UNITED STATES PATENT OFFICE.

RICHARD WALSH, OF MOBILE, ALABAMA.

MARINE BOILER.

Application filed November 28, 1919. Serial No. 341,067.

To all whom it may concern:

Be it known that I, RICHARD WALSH, a citizen of the United States, residing at Mobile, in the county of Mobile and State of 5 Alabama, have invented certain new and useful Improvements in Marine Boilers, of which the following is a specification.

This invention relates to certain new and useful improvements in Cornish or Scotch 10 marine boilers of that general type in which provision is made for more thorough utilization of the heating power, and at the same time facilitating the circulation of water and causing a more rapid generation of 15 steam. Such general type will be found in my Patent No. 1,317,744, October 7, 1919. The present invention also is applicable to fire-box boilers, as will be evident as the 20 description proceeds.

The present invention has for its objects among others to provide simple and efficient means for blowing out the sediment from the bottom of the boiler.

It has for a further object to provide simple and efficient means for thoroughly cleansing the coils with steam to remove the grease and scale which is liable to accumulate therein.

It has for a further object to provide simple and efficient means to prevent sagging of the coils, which sagging is liable to cause leakage.

I aim further at improvements in the details of construction as will hereinafter be 35 made clear.

Other objects and advantages of the invention will hereinafter appear and the novel features thereof will be particularly pointed out in the appended claim.

The invention is clearly illustrated in the accompanying drawings, which, with the numerals of reference marked thereon, form a part of this specification, and in which—

Figure 1 is a vertical longitudinal section 45 through the rear end of the boiler, with parts in section and a portion broken away.

Figure 2 is an end view, looking from the right of Figure 1.

Like numerals of reference indicate like 50 parts throughout the several views.

My present improvement may be placed in the back connection of the furnace or in any other suitable position, although that herein illustrated is what I, at the present 55 time, consider preferable. It is evident, however, that the invention is not restricted

to this exact disposition of the parts, the right being reserved to make such changes and variations as come fully within the scope of the appended claim. 60

In the present instance I have shown the improvements as applied to a boiler 1, of which 2 is the rear end or head.

3 are the tubes of the boiler of well-known construction. 65

Referring first to Figure 1, 4 designates a pipe extending within the lower portion of the boiler, being disposed as low as practical therein and outside the head or end 2 of the boiler is provided with a valve 5. 70

6 is a pipe connected by suitable coupling 7 with the pipe 4 outside the boiler, and rising from this pipe 6 is a pipe 8 from the upper end of which extends the lateral pipe 9 passed through the end of the boiler and 75 through a suitable encircling sleeve or the like 10, and within the boiler provided with a coil 11 which extends back and forth transversely of the boiler, as seen best in Figure 2. 80

Connected with the upper end of the coil is a pipe 12 extended through the head or end 2 and through a suitable protecting sleeve or the like 13. Connected with this pipe 12 is an upwardly extended pipe 14 85 from which extends the lateral branch 15 provided with a valve 16 and communicating with the pipe 17 extending within the upper portion of the boiler just below the water level, as seen in Figure 1. Extended 90 upward from the connection 18 between the pipes 14 and 15 is a steam pipe 19 provided at its upper end with a controlling valve 20 at the junction of said pipe 19 and a pipe 21 connected with the steam dome, 22, and provided with a valve 23. 95

24 is a pipe connected with the pipe 6 and provided with a valve 25. 28 is a check valve in the pipe 6, as seen in Figure 2.

27 is a pipe shown as vertically disposed 100 and at its upper end provided with a three-way valve 28 controlling the flow from the feed pump through the pipe 29, the flow to the boiler through the pipe 30 and the flow through the pipe 27 to the heating coil or 105 system within the end of the fire-box, as indicated by the arrows in Figure 1. 31 is a valve controlling the flow through the pipe 27 into the pipe 9 and thence into the coil 11. 32 is a check valve in the connection between the pipe 27 and the valve 31, as seen 110 clearly in Figure 2.

As indicated in Figure 2, the boiler is of the type embodying three furnaces 33, 34 and 35, indicated by dotted lines.

As will be clearly understood upon reference to Figures 1 and 2, the valve 16 controls the feed entrance from the heater or coil 11 to the boiler through the pipe 17, seen in Figure 1.

In operation, when it is desired to feed 10 the water through the heater or coil 11, the cut-out valve 31, the boiler feed valve 16 and the bottom circulating valve 5 are opened and the three-way valve 28 turned so as the water will flow through the pipe 29 15 and thence through the pipes 27 and 9 into the coil 11. When it is desired to cut out the heater, the three-way valve 28 is turned so as to close the flow through the pipe 29 to the pipe 27 and the valves 31, 16 and 5 20 closed. When it is desired to blow out the sediment from the bottom of the boiler, which it is desirable to do at intervals so as to get rid of the sediment and prevent its accumulation and ultimately passing up 25 into the pipe and coils and stopping the circulation and causing the coils to burn, the valve 25 is opened and the sediment will be blown out through the bottom blow-out pipe 4—6—24.

30 In order to thoroughly clean the coils with steam, the valves 16 and 5 are closed, the bottom blow-out valve 25 is opened and the valves 20 and 23 opened so as to turn on the steam and the latter passing through 35 the coils will heat them and the grease so that the scale and grease in said coils will pass out through the bottom blow valve 25. This will serve to keep the coils perfectly clean and free of grease and scale which, 40 unless blown out occasionally, will gradually accumulate in the coils, and both the grease and scale being non-conductors of heat, the heat will not pass into the boiler. Furthermore, the coils will burn, the same 45 as will a furnace under similar conditions, due to the high temperature to which they are exposed. I find that the steam is a simple, practical and economical means for cleaning the grease from the coils and, at 50 the same time, it cracks the scale which passes out through the bottom blow-out

pipe. In lieu of a single connection from the coils to the feed entrance from the heater to the boiler, I may sometimes employ two, as shown in Figure 2, wherein 55 the pipe 35^a is employed which is connected with the coil and also controlled by the valve 16. This is accomplished by making an additional opening from the back connection through the back head, and a tube 60 of ample size expanded. This makes three 65 openings in the back head and back connection, as shown, and this constitutes a rigid brace or support for the back of the coils, doing away with any chance of the coils sagging due to constant vibration when the vessel is running. This sagging of the coils is liable to cause a leak as the elbows into which the extensions are engaged 70 may start just enough to leak and put the coil out of commission. With the double support, the liability of a downward sag 75 or movement is entirely eliminated. To insure that the water is carried as intended through the coils, the opening through this pipe is reduced just enough opening being left for a slight circulation. The length of the coils is varied to suit the individual boiler.

80 What I claim as new is:

In a boiler, a heater coil, a pipe extended within the lower portion of the boiler and provided outside the boiler with a valve, a pipe connected with said pipe, a pipe rising from the last-named pipe, a lateral branch therefrom connected with said coil, a pipe leading from the upper part of the coil, an upwardly-extended pipe leading from the last-named pipe and having a lateral branch 85 with a valve, a pipe connected with said branch and extended within the upper part of the boiler below the water line, a steam pipe connected with the steam dome and with said branch and provided with a valve, a pipe extended upwardly and connected 90 with the boiler and having means for connection with a feed pump, and a three-way valve controlling the flow from the feed pump, the flow to the boiler, and the flow 95 through said pipe to the heater coil. 100

In testimony whereof I affix my signature.

RICHARD WALSH.
